UNITED STATES PATENT OFFICE.

ELMER O. BEARDSLEY, OF CHICAGO, AND WALTER F. PIPER, OF OAK PARK, ILLINOIS,
ASSIGNORS TO THE BEARDSLEY & PIPER COMPANY, OF CHICAGO, ILLINOIS, A COR-
PORATION OF ILLINOIS.

MOLDING MACHINE.

Application filed July 9, 1921, Serial No. 483,385. Renewed January 12, 1928.

The invention relates to molding machines. In the practice of the inventions set forth in Letters Patent No. 1,309,833, dated July 15, 1919 and No. 1,335,641, dated March 30, 5 1920, it has been found difficult in some foundries to use a stationary sand projector and in other instances a layer of sand on the floor traversed by the portable machine cannot be conveniently provided.

10 The object of the present invention is to provide an improved molding machine of the portable type which is adapted to carry a sufficient supply of sand on its own carriage to fill a row of molds. In this manner, it be- 15 comes possible to propel the machine to the place in the foundry where the sand is treated and kept, to there load the machine with sufficient sand to fill a row of molds and then to return to the sand pile for another load.

20 With such a structure, it is not necessary to provide a sand pile on the floor traversed by the machine and the invention makes it possible to use a machine of the tractor type in foundries where the equipment does not 25 permit of the use of sand on the floor traversed by the machine.

Other objects of the invention will appear from the specification.

The invention consists in the several novel 30 features hereinafter set forth and more particularly defined by claims at the conclusion hereof.

In the drawings: Fig. 1 is a side elevation of a machine embodying the invention. Fig. 35 2 is a plan. Fig. 2^a is a view of the reservoir bottom and its driving mechanism. Fig. 3 is a vertical section. Fig. 4 is a rear elevation. Fig. 5 is a section on line 5—5 of Fig. 1. Fig. 6 is a section taken on line 6—6 of Fig. 40 3. Fig. 7 is a transverse section on line 7—7 of Fig. 3. Fig. 8 is a detail of the pawl and ratchet driving mechanism for the traction-wheels.

The several mechanisms of the machine are 45 mounted on a carriage comprising a frame 8 composed of sides rigidly secured together, carrying-wheels 9 and traction-wheels 10 adapted to run on rails 12 on the floor of the foundry. A molding machine 15 comprises 50 a sand projector 60 at the outer end of a jib 71 which is pivoted to an arm 72 which, in turn, is pivoted on a column 16 which is fixed to the truck frame. A motor 73 is adapted to drive the rotor of the projector 60 and a feed-

belt 74 carried by the jib, to supply sand to 55 the projector. A vibratory chute and riddle 17 are adapted to deliver sand to the belt 74. The molding machine illustrated is of the type exemplified in our patent No. 1,309,833, dated July 15, 1919 and in an application 60 filed by us March 14, 1921, Serial No. 452,068, to which reference may be had for a fuller description thereof.

An elevator, to deliver sand from a pile into a reservoir 18 on the carrier, consists of an 65 endless chain 20 and buckets 21 secured on the chain. Chain 20 passes around an over-head driving sprocket 22 which is fixed to a shaft 23 which is mounted in bearings 24 secured to the upper portion of the reservoir 18. 70 The lower portion of the chain passes around a sprocket 25 which is fixed to a hollow shaft 26 which is provided with spiral conveyor blades 27 which are adapted to convey sand from the sides of a pile laterally to the buck- 75 ets 21 of the elevator. Conveyor-shaft 26 is movably mounted in the lower ends of a pair of arms 28 which are pivoted, at 29, in brackets 30 which are fixed to the frame sides of the truck. The purpose in movably mounting 80 the conveyor shaft and the sprocket 25 thereon is to make provision for lifting them to an elevated position above the foundry room floor after the reservoir 18 has been loaded with sand and so that they will clear the floor 85 under the truck frame. One of the supporting arms 28 is provided with a rack 31 with which meshes a worm 32 which is operable by a hand-wheel 33 on a shaft which is mounted in bearings 34 on the upper end of one of the 90 brackets 30. By rotating the hand-wheel 33, the lower portion of the elevator and the cross-conveyor may be raised into position shown by dotted lines in Figs. 1 and 3. An idler sprocket 35 is mounted on a stud 36 and is located so that the elevator chain 20 will 95 be kept operative and retained on the sprockets 25, 22 when the cross-conveyor and elevator are raised. This construction exem- 100 plifies mechanism by which the lower portion of the elevator and the cross-conveyor may be raised and lowered, so the cross-conveyor may be operated at different elevations to take sand from different elevations of a stored pile.

When the reservoir is to be loaded, the carriage is propelled so as to bring the lower portion of the elevator and the cross-conveyor

- into a pile of sand, so that the cross-conveyor will move the sand from the sides inwardly to the elevator and the elevator buckets will be filled while the elevator is being operated.
- 5 The cross-conveyor and lower portion of the elevator may be adjusted to remove sand from different elevations of a pile or from piles of different heights.
- An electric motor 38 is mounted on the truck and gearing is provided to drive the elevator and cross-conveyor from the motor. The shaft of the motor is provided with a pinion 39 which meshes with a gear 40 on a cross-shaft 41 which is mounted in bearings 42 secured to the truck-frame. A pinion 43 is slideable on, and secured to rotate with, shaft 41. A gear 44 on a shaft 45 which is mounted in a bearing 46 meshes with pinion 43. The mechanism for driving the loading 10 mechanism comprises a sprocket 47 which is fixed to a shaft 45, a chain 48 driven by sprocket 47 and a sprocket 49 fixed to the outer end of the shaft 23 to which the upper elevator-sprocket 22 is secured. Pinion 43 is slideable into and out of engagement with gear-wheel 44 to render operative or inoperative the cross-conveyor and the sand loading mechanism, so that it may be rendered operative while loading the reservoir 18 and inoperative when the machine is filling molds or is in transit between the sand pile and the place where the flasks are placed.
- A screen 51 is supported over the top of the reservoir 18 and is mounted in a frame 52 which is movably supported by resilient bars 53 which have their upper ends secured to said frame and their lower ends secured to the wall of said reservoir. This screen separates any castings or scrap from the sand 15 and is vibrated by a bell-crank-lever 54 which is fulcrumed, at 55, pivoted to the screen-frame 52, at 56, and is operated by a link 57, the lower end of which is pivoted to a wrist-pin 58 which rotates with gear 44. The screen 51 will sift the sand and separate the scrap or other material therefrom while the sand loading mechanism is being operated. In practice, the loading mechanism and screen 51 will be conjointly operated adjacent a 20 supply of sand until the reservoir contains a sufficient supply of sifted sand to fill a run of molds. The wrist-pin 58 for driving the sifting mechanism, being on gear 44, will be rendered operative and inoperative with the loading mechanism. Opening 75 formed in the reservoir 18 is closed by a door 76 which may be opened to permit any excess of sand to be discharged from the reservoir and to provide access to the inside of the reservoir.
- 25 The truck is adapted to be propelled at a high speed between the sand-supply and the place where the flasks are filled by mechanism driven by power derived from the motor 38. This mechanism comprises a gear-wheel 77 secured to each traction-wheel 10, gear-
- wheels 80, fixed to the ends of a cross-shaft 78, and meshing with the gears 77 respectively, a gear 85 loose on shaft 78 and provided with clutch-teeth 86 which are adapted to drive a clutch-member 87 which is 70 slideable on and fixed to rotate with shaft 78 and pinion 88 which meshes with gear 85 and is fixed to, and constantly driven by, the shaft 41 which is driven by gears 40 and 39. Motor 38 is of the reversible type so that the 75 carriage may be driven forwardly or backwardly, and the direction is controlled by the usual motor-switches (not shown) provided for such purpose. A lever 89 is adapted to shift clutch-member 87 into and out of 80 operative connection with the teeth 86 of gear 85 to control the propulsion of the machine by the high speed driving mechanism.
- Sand is delivered in regular quantity from the reservoir 18 to the chute 17 to keep the 85 projector supplied with sand to fill the flasks in making molds. For this purpose, the bottom 98 of the reservoir 18, is rotatable and secured to a vertical shaft 99 which is mounted in an anti-friction bearing 100 on the carriage-frame and a deflector bar 101 directs the sand moved by the bottom through an opening 102 in one side of the reservoir 18. Bar 101 is fixedly secured in any suitable manner in the lower portion of the reservoir 95 and is disposed so the sand urged against it by the rotating bottom 98 will be crowded laterally through opening 102 where the sand will be caught by the elevator-buckets 103 on an endless chain 104 which passes around a 100 lower sprocket 105 on a shaft 106 and an upper sprocket 107 on a stud-shaft 108. The buckets 103 are adapted to discharge the sand into the chute 17 on the projector. Shaft 108 is carried by a lever 109 which is pivoted to 105 a bracket 110 fixed to the upper portion of the reservoir and to which a spring 111 is applied to act on the lever to keep the elevator-chain 104 taut. Shaft 106 is connected to rotate the reservoir-bottom 98 by a pinion 110 112 which is fixed to said shaft and meshes with a ring-gear 113 which is fixed to the underside of said bottom. Shaft 106 is driven by a sprocket 114 which is loose on the hub of, and has a one-way clutch-connection 115 115 with, gear 85, a chain 116 driven by said sprocket and driving a sprocket 117 fixed on shaft 106. A lever 118 is provided to shift sprocket 114 into and out of operative connection with gear 85. A spring 119 is applied to urge this lever into position to keep sprocket 117 in driving relation with gear 85 and a removable pin is adapted to lock the lever in its alternative position. The one-way clutch 115 permits the carriage to be 120 propelled in one direction at high speed without the necessity of locking lever 118 in said alternative position.
- While filling flasks, it is desirable to propel the carriage slowly to bring the projector 130

within operative range of the successive flasks in rows at the sides of the track on which the carriage travels while the flasks are being filled. The mechanism for this purpose comprises a cam 91 on the hub of the constantly driven gear 85, a lever 92 pivoted to the carriage-frame at 93, and provided with a roller 94 riding on said hub and cam, a pawl 95 pivoted to, and operated by, lever 92, and a ratchet-wheel 96 which is integral with one of the gears 80, and is operated step-by-step by said pawl. This driving mechanism may be rendered inoperative by swinging the lever 92 out of operative relation with cam 91, which is desirable when the high-speed propelling mechanism is operative or when it is desired to operate the molding machine as a stationary machine.

In operation, the machine will be propelled at high-speed so the cross-conveyor and loading elevator-buckets will pass into a pile of sand. The driving mechanism for said conveyor and elevator will then be rendered operative to cause the elevator to lift the sand and discharge it into the screen 51. The sifted sand will fall into the reservoir 18. In loading the reservoir, the cross-conveyor may be adjusted in the pile of sand and will serve to fill the buckets. During this loading operation, the propelling mechanism and the mechanism for delivering sand from the reservoir to the projector will be idle. The operation of the loading apparatus will be continued until the requisite quantity of sand has been sifted and delivered into the reservoir 18. Then, pinion 43 is disconnected from gear 44 to render the loading mechanism inoperative and clutch 86, 87 will be rendered operative so the carriage will be propelled at the high speed by its driving mechanism to the place where a row of flasks to be filled have been placed alongside of the track, and then said mechanism will be rendered inoperative by shifting lever 89 to disconnect clutch 87, 86. Next, lever 118 is then released to permit spring 119 to retain the clutch 115 operative, the lever 92 will be swung into operative relation with cam 91, and pawl 95 placed into operative relation with ratchet-wheel 96. The rotatable bottom 98 will then be driven to discharge sand through opening 102 into the elevator-buckets 103 which will be driven while the bottom is rotating and will elevate regular quantities of sand and discharge it into and keep the chute 17 supplied with sand for delivery to the projector 60 by the conveyor-belt 74. The operator will move the projector which is movably connected to the carriage by arm 72 and jib 71 over flasks within working range of, and below, the projector. During this operation, the lever 92 will be intermittently operated to operate pawl 95 to step up ratchet-wheel 96 so that the machine will be automatically propelled while the projector

and sand-feeding mechanism are operated to bring the projector within range of the successive flasks in one or more rows along the track.

When all of the load of sand in the reservoir has been used in the projector, the driving mechanism for the feed-bottom 98, the elevator buckets 103 and ratchet 96 will be rendered inoperative at clutch 115. Clutch 86, 87 will then be rendered operative to speedily drive the machine back to the sand pile for another load.

The invention exemplifies a portable molding machine which is adapted to load sand from a pile to retain the load of sand in a reservoir on the carriage and to feed the sand from the reservoir to the machine for filling flasks on the molding room floor until the entire load has been projected into the flasks.

The invention is not to be understood as restricted to the details set forth, since these may be modified within the scope of the appended claims, without departing from the spirit and scope of the invention.

Having thus described the invention, what we claim as new and desire to secure by Letters Patent, is:

1. In a machine for making molds for founding, the combination of a movable carriage, a machine for filling flasks mounted on the carriage, a sand-reservoir on the carriage adapted to retain sufficient sand for a run of flasks, mechanism for feeding sand from the reservoir to the filling machine and driving mechanism for said sand feeding mechanism.

2. In a machine for making molds for founding, the combination of a movable carriage, a machine mounted on the carriage for filling flasks, a sand reservoir on the carriage of sufficient capacity to retain sand for a run of flasks, mechanism on the carriage for loading sand from a pile into the reservoir, and mechanism operable separately from the loading mechanism for feeding sand from the reservoir to the flask filling machine.

3. In a machine for making molds for founding, the combination of a movable carriage, a machine, mounted on the carriage, for filling flasks, a sand reservoir on the carriage of sufficient capacity for a run of flasks, mechanism on the carriage for loading sand into the reservoir from a pile, means for feeding sand from the reservoir to the filling machine, and mechanisms for separately driving the loading mechanism and the sand feed mechanism so they may be independently operated.

4. In a machine for making molds for founding, the combination of a movable carriage, a machine for filling flasks mounted on the carriage, a sand-reservoir on the carriage, and mechanism on the carriage for loading sand from a pile into the reservoir, comprising an elevator and a cross-conveyor.

5. In a machine for making molds for

12. In a machine for making molds for founding, the combination of a movable carriage, a machine for filling flasks mounted on the carriage, a sand-reservoir on the carriage adapted to retain sufficient sand to fill a run of flasks, propelling mechanism on and for the carriage, mechanism for feeding sand from the reservoir to the filling machine and driving mechanism for said feed means. 70
13. In a machine for making molds for founding, the combination of a movable carriage, a machine for filling flasks mounted on the carriage, a sand-reservoir on the carriage of sufficient capacity to hold sand for a run of flasks, propelling mechanism on and for the carriage, and mechanism on the carriage for loading sand from a pile into the reservoir. 75
14. In a machine for making molds for founding, the combination of a movable carriage, a machine for filling flasks mounted on the carriage, a sand-reservoir on the carriage of sufficient capacity to retain a supply of sand for a run of flasks, propelling mechanism on and for the carriage, mechanism on the carriage for loading sand from a pile into the reservoir, and mechanism for raising and lowering the loading mechanism. 80
15. In a machine for making molds for founding, the combination of a movable carriage, a machine for filling flasks mounted on the carriage, a sand-reservoir on the carriage of sufficient capacity to hold sand for a run of flasks, propelling mechanism on and for the carriage, mechanism on the carriage for loading sand from a pile into the reservoir, and means operable independently of the loading mechanism for feeding sand from the reservoir to the filling machine. 85
16. In a machine for making molds for founding, the combination of a movable carriage, a machine for filling flasks mounted on the carriage, a sand-reservoir on the carriage, propelling mechanism on and for the carriage, an elevator on the carriage for delivering sand into the reservoir and means for raising and lowering the lower portion of the elevator. 90
17. In a machine for making molds for founding, the combination of a movable carriage, a machine for filling flasks mounted on the carriage, a sand reservoir on the carriage, mechanism for loading sand into the reservoir, a screen for the sand in transit to the reservoir to which the sand is delivered by the loading mechanism, and mechanism on the carriage for driving the loading mechanism and operating the screen. 95
18. In a machine for making molds for founding, the combination of a movable carriage, a machine for filling flasks mounted on the carriage, a sand-reservoir on the carriage, mechanism for loading sand into the reservoir, a screen for the sand in transit to the reservoir, mechanism on the carriage for driving the loading mechanism and operating the screen, and means for conjointly controlling the operation of the loading mechanism and the screen. 100
19. In a machine for making molds for founding, the combination of a movable carriage, a machine for filling flasks mounted on the carriage, a sand-reservoir on the carriage, a cross-conveyor and an elevator for sand, and means for raising and lowering the cross-conveyor and the lower portion of the elevator. 105
20. In a machine for making molds for founding, the combination of a movable carriage, a machine for filling flasks mounted on the carriage, a sand-reservoir on the carriage of sufficient capacity to hold sand for a run of flasks, propelling mechanism on and for the carriage, mechanism on the carriage for feeding sand from the reservoir to the filling machine, and mechanism on the carriage, operable independently of the sand feed mechanism for loading sand from a pile into the reservoir, comprising an elevator and a cross-conveyor. 110
21. In a machine for making molds for founding, the combination of a movable carriage, a machine for filling flasks mounted on the carriage, a sand-reservoir on the carriage of sufficient capacity to hold sand for a run of flasks, mechanism on the carriage for loading sand from a pile into the reservoir, and mechanism for raising and lowering the loading mechanism. 115
22. In a machine for making molds for founding, the combination of a movable carriage, a machine for filling flasks mounted on the carriage, a sand-reservoir on the carriage, an elevator on the carriage for delivering sand into the reservoir, and means for raising and lowering the lower portion of the elevator. 120
23. In a machine for making molds for founding, the combination of a movable carriage, a machine for filling flasks mounted on the carriage, a sand-reservoir on the carriage, a cross-conveyor and an elevator for sand, and means for raising and lowering the cross-conveyor and the lower portion of the elevator. 125
24. In a machine for making molds for founding, the combination of a movable carriage, a machine for filling flasks mounted on the carriage, a sand-reservoir on the carriage, a screen over the reservoir, an elevator for delivering sand into the screen and mechanism for operating the screen. 130

5 founding, the combination of a movable carriage, a machine for filling flasks mounted on the carriage, a sand-reservoir on the carriage, mechanism to feed sand from the bottom of the reservoir to the filling machine and driving mechanism for said feed mechanism.

10 20. In a machine for making molds for founding, the combination of a movable carriage, a machine for filling flasks mounted on the carriage, a sand-reservoir on the carriage, a movable bottom for the reservoir, and means to feed sand from the bottom to the filling machine.

15 21. In a machine for making molds for founding, the combination of a movable carriage, a machine for filling flasks mounted on the carriage, a sand-reservoir on the carriage, a rotatable bottom for the reservoir, means to rotate said bottom, and means to feed sand

20 from the bottom to the filling machine.

25 22. In a machine for making molds for founding, the combination of a movable carriage, a machine for filling flasks mounted on the carriage, a sand reservoir on the carriage, said reservoir having an opening in its side adjacent its bottom, and an elevator for feeding sand from said opening to said filling machine.

30 23. In a machine for making molds for founding, the combination of a movable carriage, a machine for filling flasks mounted on the carriage, a sand-reservoir on the carriage, said reservoir having an opening in its side and a movable bottom to discharge sand through said opening, and means to feed sand discharged through the opening to the filling machine.

35 24. In a machine for making molds for founding, the combination of a movable carriage, a machine for filling flasks mounted on the carriage, a sand-reservoir on the carriage, and an elevator for delivering sand from the reservoir to the filling machine.

40 25. In apparatus of the character described, the combination of a carriage, a sand-reservoir on the carriage, mechanism on and for propelling the carriage, mechanism for feeding sand from the reservoir for use in a filling machine and mechanism for driving said feed mechanism.

45 26. In apparatus of the character described, the combination of a carriage, a sand-reservoir on the carriage, mechanism on and for propelling the carriage, mechanism for loading sand from a pile into the reservoir, mechanism for feeding sand from the reservoir for use in a filling machine and mechanism for driving said feed mechanism.

50 27. In apparatus of the character described, the combination of a carriage, a sand-reservoir on the carriage, mechanism on and for propelling the carriage, and an elevator for feeding sand from the bottom of the reservoir to a filling machine.

55 28. In apparatus of the character de-

scribed, the combination of a carriage, a sand-reservoir on the carriage, mechanism on and for propelling the carriage, a screen over the reservoir through which the sand is delivered into the reservoir, and mechanism for feeding sand from the reservoir for use in a filling machine.

60 29. In apparatus of the character described, the combination of a carriage, a reservoir on the carriage, a movable bottom for the reservoir, mechanism for operating the bottom, and means to feed sand from the bottom to a filling machine.

65 30. In apparatus of the character described, the combination of a carriage, a reservoir on the carriage, a movable bottom for the reservoir, mechanism for operating the bottom, and an elevator to feed sand from the bottom of the reservoir to a filling machine.

70 75 31. In apparatus of the character described, the combination of a carriage, a reservoir on the carriage, a rotatable bottom for the reservoir, an elevator to feed sand from the bottom for use in a filling machine, and mechanism for operating the bottom and to drive the elevator.

75 80 85 90 95 32. In apparatus of the character described, the combination of a carriage, a sand reservoir on the carriage of sufficient capacity to retain a supply of sand for a run of molds, mechanism to feed sand from the reservoir for use in a filling machine, comprising a motor and gearing driven thereby, and mechanism on the carriage for propelling it.

100 105 33. In a machine for making molds for founding, the combination of a movable carriage, a machine for filling flasks mounted on the carriage, a sand-reservoir on the carriage, means to feed sand from the reservoir to the filling machine, mechanism comprising a motor on the carriage to propel it, while the feed-means is in operation to bring the filling machine into position to successively fill flasks.

110 115 120 125 34. In a machine for making molds for founding, the combination of a movable carriage, a machine for filling flasks mounted on the carriage, a sand-reservoir on the carriage means to feed sand from the reservoir to the filling machine, mechanism to propel the carriage while the feed-means is in operation to bring the filling machine into position to successively fill flasks, and high-speed mechanism to propel the carriage when the filling machine is not in operation.

35 36. In a machine for making molds, the combination of a movable carriage, a rotary sand projector mounted on the carriage, a reservoir for sand on the carriage, mechanism to drive the projector, and means to feed sand from the reservoir to the projector.

130 37. In a machine for making molds, the combination of a movable carriage, a rotary sand projector mounted on the carriage, a reservoir for sand on the carriage, mechanism

to drive the projector, mechanism to propel the carriage, and means to feed sand from the reservoir to the projector.

37. In a machine for making molds, the combination of a movable carriage, a rotary sand projector mounted on the carriage, a reservoir for sand on the carriage, mechanism to drive the projector, mechanism to load the reservoir, and means to feed sand from the reservoir to the projector.

38. In a machine for making molds, the combination of a movable carriage, a rotary sand projector mounted on the carriage, a reservoir for sand on the carriage, mechanism to drive the projector, an elevator to load sand from a pile into the reservoir, and means to feed sand from the reservoir to the projector. 15
